UNITED STATES PATENT OFFICE.

CHRISTIAN G. HOERLE, OF TORRINGTON, CONNECTICUT, ASSIGNOR TO
UNION HARDWARE COMPANY, OF TORRINGTON, CONNECTICUT.

ROLLER-SKATE.

No. 823,333.

Specification of Letters Patent.

Patented June 12, 1906.

Application filed January 4, 1906. Serial No. 294,570.

To all whom it may concern:

Be it known that I, CHRISTIAN G. HOERLE, a resident of Torrington, in the county of Litchfield and State of Connecticut, have invented certain new and useful Improvements in Roller-Skates; and I do hereby declare the following to be a full, clear, and exact description of the invention, such as will enable others skilled in the art to which it appertains to make and use the same.

My invention relates to improvements in roller-skates, and more particularly to such as employ a sheet-metal foot-plate, one object of the invention being to so construct a skate of this class that the sheet-metal foot-plate shall be rigid and capable of effectually withstanding all strains to which it may be subjected.

A further object is to provide a skate with means which will serve to brace the foot-plate and also the truck-brackets and which will also provide bearings for the screws of the clamps.

With these objects in view the invention consists in certain novel features of construction and combinations and arrangements of parts, as hereinafter set forth, and pointed out in the claims.

In the accompanying drawings, Figure 1 is a side elevation of a roller-skate embodying my improvements. Fig. 2 is a longitudinal view. Fig. 3 is a transverse sectional view on the line *x* *x* of Fig. 1, and Fig. 4 is a transverse sectional view on the line *y* *y* of Fig. 1.

1 represents the sheet-metal foot-plate of the skate. In order that this foot-plate shall possess adequate strength and rigidity to withstand all strains which may be brought to bear upon it, especially when the skate is worn in the rink by experts, I provide a longitudinal rib 2, which extends from the heel portion to a point in proximity to the toe on the bottom of the foot-plate. This rib may consist of a sheet-metal strip disposed edge-wise against the bottom face of the foot-plate and riveted to the latter by means of integral lugs 3, which project upwardly through holes in the foot-plate and upset at their upper ends.

Adjustable clamps 4 for securing the skate to the shoe of the user are provided near the toe and heel portions. Each clamp comprises two members having guide-slots for the

reception of headed pins secured to the foot-plate, and said members of the clamp are made with depending lugs disposed at respective sides of the strengthening-rib 2 and are provided with threaded openings for the reception of clamping-screw 5. Each clamping-screw is made with right and left hand threads separated by a plain central portion, and the rib is made with notches 6, in which the plain portions of the screws are disposed. In this manner longitudinal movement of the clamp-screws is prevented when said screws are turned to adjust the clamp members.

Sheet-metal truck-brackets 7 straddle the strengthening-rib 2 and are provided with integral lugs, by means of which said brackets are riveted to the foot-plate 1. One end of each truck-bracket has a bearing against the strengthening-rib 2, and said brackets are braced against endwise strain by shoulders 8 on the rib, against which shoulders the brackets bear.

Wheeled trucks 9 are mounted in the brackets 7 in a manner well understood.

With my improvements the foot-plate and truck-brackets are effectually braced, and simple and efficient means are provided to insure the accurate operation of the clamps.

Having fully described my invention, what I claim as new, and desire to secure by Letters Patent, is—

1. In a skate, the combination with a foot-plate, of a strengthening-rib disposed edge-wise against the under face of the foot-plate and secured thereto, said strip extending continuously from the head portion of the foot-plate to a point in proximity to the toe of the foot-plate, truck-brackets secured to the foot-plate and straddling the rib and trucks attached to said truck-brackets.

2. In a skate, the combination with a sheet-metal foot-plate, of a sheet-metal strip having integral lugs on its upper edge riveted to the foot-plate, said strip extending continuously from the heel portion of the foot-plate to a point in proximity to the toe of the foot-plate, sheet-metal truck-brackets riveted to the foot-plate and straddling said sheet-metal strip, and trucks attached to said sheet-metal truck-brackets.

3. In a skate, the combination with a foot-plate, of a strengthening-rib secured longitudinally to the under face thereof and truck-

brackets straddling said rib, said rib engaging said brackets to serve as a brace for the same.

4. In a skate, the combination with a foot-
5 plate, a longitudinal strengthening-rib on the
bottom thereof, said rib having shoulders on
its lower edge, and truck-brackets secured
to the foot-plate, straddling said rib and bearing
against the shoulders on the latter.
- 10 5. In a skate, the combination with a foot-
plate, a clamp and a screw for operating the

clamp, of a strengthening-rib on the bottom
of the foot-plate and having notches to receive
the plain intermediate portion of the
clamp-screw.

In testimony whereof I have signed this
specification in the presence of two subscr-
ing witnesses.

CHRISTIAN G. HOERLE.
